PHONOGRAPH RECORD HOLDER
OR THE LIKE

Daniel C. Clark, 1949 Las Tunas Road,
Santa Barbara, Calif. 93103

Filed June 6, 1966, Ser. No. 2,582

Term of patent 14 years

(Cl. D33—10)

FIG. 1

FIG. 2

FIG. 4

FIG. 3

FIG. 5

FIGURE 1 is a perspective view of the phonograph record holder or the like, showing my new design;

FIGURE 4 is a perspective view thereof as it appears with the intermediate spacing rods removed; and

I claim:

The ornamental design for a phonograph record holder or the like, substantially as shown and described.
